UNITED STATES PATENT OFFICE.

JAMES M. HYDE, OF PALO ALTO, CALIFORNIA.

APPARATUS FOR THE CONCENTRATION OF ORES.

1,296,190.

Specification of Letters Patent.

Patented Mar. 4, 1919.

Application filed December 23, 1915. Serial No. 68,213.

To all whom it may concern:

Be it known that I, JAMES M. HYDE, a citizen of the United States, residing at Palo Alto, in the county of Santa Clara and State of California, have invented certain new and useful Improvements in Apparatus for the Concentration of Ores, of which the following is a specification.

- My invention relates to an apparatus for separating metalliferous minerals from the associated gangue, and, in some instances, the separation of one metalliferous mineral from another by flotation. Generally speaking, the type of process to which my process is applicable consists in subjecting the ore pulp in a proper state of dilution, and with proper reagents mixed therewith, to the influence of an upward current of bubbles of air or other gas, the bubbles being admitted to the pulp through a porous medium below the surface of the pulp. In such a process the part of the material to be separated from the remainder adheres to the air bubbles as they rise through the pulp, and a mass of mineral-bearing bubbles is formed upon the surface and carried over the edge of the containing vessel. It has long been known that when certain substances are added to an ore pulp, the selective adhesion of certain of the metalliferous mineral particles for the pulp, or air, or other gas, can be utilized in the manner above described. The substances so added to the pulp may be substances insoluble in water, such as oleic acid, commonly known as candlemakers' red oil, cotton-seed oil, eucalyptus oil, or many other oils; or the substances added to the water for the purpose mentioned may be soluble in water, for instance, cresol, phenol, acetic acid, or certain of the alcohols. When insoluble substances are used for the purpose mentioned, it is necessary that they be mixed with the ore pulp with sufficient thoroughness to finely subdivide the insoluble substances used. It has also been found that certain substances, such as coal tar, or wood tar, containing both water-soluble and water-insoluble ingredients, may be used for the purpose above mentioned.
- Apparatus has heretofore been used for carrying out the process above described wherein the pulp containing vessel is provided with a sloping bottom composed of some porous medium such as fabric, un-

glazed porcelain, carborundum, etc., through which air is admitted from an air chamber beneath the porous medium. In such apparatus it is necessary to maintain only sufficient air pressure to counterbalance the hydrostatic head of the ore pulp and to cause the air to pass through the porous medium. In such apparatus it has been customary to admit the pulp at the shallow end of the vessel, and to permit the pulp to flow out at the deep end, the pulp during its passage through the vessel being subjected to the vertically rising stream of air bubbles admitted through the downwardly sloping porous bottom, the sloping bottom assisting in preventing the accumulation of any solid matter which might tend to settle out of the pulp during its passage through the vessel. In using such an apparatus the pulp is subjected to the rising stream of air bubbles throughout its transit through the flotation vessel or cell, and up to the very moment when it is discharged. The air bubbles passing through the pulp just before its discharge, however, have no opportunity to rise to the surface of the pulp before the pulp is discharged, and the result is that the air bubbles admitted to the pulp adjacent the discharge outlet are carried away with the pulp through the discharge port of the apparatus, without effecting any useful function. In my improved apparatus I overcome this difficulty by providing a zone near the discharge outlet of the flotation cell in which no air is admitted to the pulp, and in this zone I provide means for collecting the bubbles of air with their adhering mineral, which bubbles and mineral would otherwise be carried out through the discharge port and lost so far as the operation of the cell in question is concerned.

In the treatment of ores of different character, or in meeting the requirements incident to the variations in the same ore, or variations in the dilution of the pulp, it is desirable that the inclination of the bottom of the flotation cell be varied, and I have found that means for so varying the inclination of the bottom of the cell can be combined with the above-mentioned feature of my invention, that is, the provision of a zone near the discharge end of the cell in which no air is admitted to the pulp.

Another improvement which I have com-

bined with the adjustable porous bottom of the cell is the provision of a readily replaceable porous bottom, the same consisting of an air box provided with a porous top so arranged that when need arises the air box can readily be removed and replaced by a new one without interrupting the operation of the cell for any appreciable length of time.

10 In connection with the foregoing improvements, I provide simple means for regulating the level of the pulp in the apparatus, such regulation of level being necessary in order to maintain the proper depth 15 of bubbles upon the surface of the pulp to secure the most efficient concentration.

By proper adjustment of the slope of the porous bottom of the cell, in connection with adjustment of the level of the pulp, the apparatus, it has been found, may be so arranged as to run efficiently for long periods of time without any personal supervision or attention. Such regulation is further assisted and supplemented by provision of 25 two outlets for the tailings, one near the bottom of the cell at the discharge end thereof, which is provided with a valve for regulation, and the other consisting of an outlet pipe of adjustable height through which 30 the level of the pulp is adjusted, as above referred to.

In the drawings,—

Figure 1 is a vertical longitudinal section through a flotation cell constructed according to my invention;

Fig. 2 is a transverse section through the same upon the line 2—2 of Fig. 1, looking in the direction of the arrows;

Fig. 3 is also a transverse section of the flotation cell taken upon the line 3—3 of Fig. 1, looking in the direction of the arrows;

Fig. 4 is a fragmentary longitudinal section upon an enlarged scale of the air box shown in Fig. 1, this view being partly in section;

Fig. 5 is a plan view of the air box, as illustrated in Fig. 4;

Fig. 6 is a longitudinal section of a modified form of flotation cell, the modification consisting in constructing the air box in a plurality of independent units in order to render it possible to replace part of the porous bottom of the cell without disturbing 55 the remainder thereof.

In the drawings I have designated the flotation cell shown in Figs. 1, 2 and 3 by the letter A, this cell consisting of a rectangular box. The pulp, after previous admixture 60 with the necessary reagents, may be supplied to the apparatus through a launder 1, from which the pulp flows into an inlet box 2 projecting from the side of the cell A. A port 3 admits the pulp from the inlet box 65 2 to the interior of the flotation cell at a

point just above the upper end of the porous bottom or air box B. The air box B is supported upon a frame 4 which is pivotally supported at 5 upon trunnions mounted upon the walls of the air box at the pulp inlet end thereof. The frame 4 may be provided with any convenient means for retaining the air box B in place. In the present instance I have shown a shoulder 6 projecting upwardly from the frame 4 near its lower end for this purpose.

As illustrated in Fig. 1, the frame 4, and air box supported thereon, are in the position in which the air box has its maximum inclination, that is, the lowest end of the frame 4 rests upon the edge of the hopper A' at the point 7. At a point just beyond the lower end of the air box B, I provide the flotation cell A with a vertical partition 8 which extends downwardly to a point sufficiently above the bottom of the flotation cell to permit the necessary adjustment of inclination of the air box. For the purpose of adjusting the inclination of the air box B, I provide an adjusting rod 9, the screw-threaded upper end 10 of which passes through an opening in a plate 11 mounted upon the top of the flotation cell. A wing nut 12 affords means for raising or lowering the adjustment rod 9. At its lower end the adjustment rod 9 is pivotally connected by means of a link 13 with a lug 14 projecting from and forming part of the frame 4, which supports the air box B. By manipulation of the wing nut 12, the lower end of the frame 4, with the air box resting thereon, may be raised and lowered, such adjustment being permitted by the pivotal connection 5 between the frame 4 and the air cell A.

In order to provide a discharge opening of substantially uniform size in all inclination adjustments of the air box B, I have constructed the lower end of the partition 8 in the form of an adjustable section 8' adapted to be moved vertically between the cleats or guides 15, 16, fixed to the walls of the air cell A. The adjustable member 8' of the wall 8 is connected by means of a yoke 17 with the adjustment rod 9, whereby, when the lower end of the air box B is raised or lowered, a corresponding movement is imparted to the adjustable section 8' of the wall 8, thus preserving a substantially uniform discharge opening at the point 18 between the lower end of the wall 8 as prolonged by the adjustable section 8' and the lower end of the air box B.

The distance between the partition 8 and the end 19 of the air cell A is sufficient to permit substantially all of the air bubbles carried by the pulp as it passes through the opening 18 to rise in the compartment C before the pulp is discharged from the apparatus, the compartment C forming a zone

wherein no air bubbles are admitted to the pulp, but wherein such air bubbles as are carried by the pulp from the main compartment of the cell are given an opportunity to rise before the discharge of the pulp from the apparatus.

The pulp finds its outlet from the apparatus through two channels, one consisting of a pipe or spout 20 near the bottom of the cell, and the other a pipe 21 adjacent the top. The outlet pipe 20 is provided with a gate-valve 22, operated by means of a rod 23 extending to the top of the apparatus, and provided with a handle 24. The outlet pipe 21 10 is connected by means of a swivel joint 25 with a pipe section 26, secured to the side 19 of the cell A and communicating with the interior of the compartment C thereof through a port 27. The port 27 is located 15 below any point at which it may ever be necessary to adjust the pulp level in the apparatus. A box or guard 64 leading from the lower part of compartment C to the port 27 still further prevents the outflow of concentrates. By rotating the outlet pipe 21 in 20 a vertical plane upon the swivel joint 25, the height of the outlet opening at the end of the pipe 21 may be regulated, thereby regulating the pulp level in the apparatus.

By suitable adjustment of the gate-valve 22 in the lower tailings outlet pipe 20, the amount of pulp discharged through the lower outlet 20 and the level regulating outlet 21 may be adjusted in such manner as to 25 secure the proper ratio between the out-flow at the two points mentioned. The sloping hopper walls A', A² guide the pulp to the outlet leading to gate-valve 22.

The air box B is shown in detail in Figs. 4 and 5, and consists of a rigid bottom member 28 having upwardly-projecting sides 29, and open at the top. This rigid bottom member 28 may be constructed of wood, cast or pressed metal, or any suitable material. The top of the air box consists preferably of a layer of fabric, such as canvas, or several superposed layers thereof. The porous top 30 formed of canvas, or other suitable material, as above stated, is stretched over the top of the air box and its edges folded down around the sides of the air box, and beneath a flange 31 formed thereon. The flange 31 is provided with a groove 32, and the canvas is held in place by means of wood or metal strips 33, by means of which the canvas is forced into the groove 32 and held therein by means of cap screws 34 threaded into the material of which the bottom member of the air box is constructed.

Air is supplied to the interior of the air box from an air main 35 through an air pipe or hose 36, a valve 37 being provided for the purpose of regulating the amount of air supplied to the air box from the air main. The air pipe 36 may be connected to the air box

by the use of any suitable coupling. In the present instance I have shown a threaded pipe section 37 clamped to the canvas top of the air box by means of nuts 38 and 39, a washer 40 being interposed between the nut 39 and the canvas, if necessary. Threaded to the upper end of the pipe 37 is a nipple 41, to which the pipe or flexible hose 36 is connected. In order to impart some degree of rigidity to the canvas top 30 of the air box, I have shown a rib 28^a extending from end to end of the box and a rigid strip 42, which may be of wood or metal, extending over the top of the canvas top and the said rib longitudinally thereof. The rigid supporting strip 42 may be clamped between the nut 39 and the rib 28^a which hold the coupling section 37 in place, and preferably the strip 42 is riveted to the canvas at a plurality of points, as indicated by the rivets 43. Obviously, other means may be adopted for imparting the necessary rigidity to the canvas top of the air box.

Extending longitudinally of the main compartment of the cell A, upon each side 90 thereof, I provide launders 44 to receive the mineral-bearing bubbles which overflow therefrom, over the lips 45. The beveled strip 65 which is secured to the partition 8 near its top serves to divert the bubbles from the partition 8 and to assist in causing the froth or bubbles to flow toward the feed end, where, if they break, it will be over ascending air bubbles.

In operation the admission of air to the pulp from the air box B causes a considerable mass of bubbles to be built up upon the surface of the pulp in the main compartment of the flotation cell A above the air box. This mass of bubbles varies in thickness in 100 different instances, often having a thickness of ten or twelve inches. In the compartment C, however, to which no air is supplied directly, but in which bubbles rise only by virtue of the air bubbles carried by the pulp, as 105 it passes beyond the stream of bubbles rising from the air box, the thickness of the mass of bubbles upon the surface will not ordinarily be so great as in the main compartment of the cell over the air box. In order to collect and save the mineral-bearing air bubbles that rise in the compartment C it is necessary to provide a supplemental overflow outlet therefor, and preferably such supplemental overflow outlet is made adjustable in 110 height in order to preserve the proper relation between such supplemental overflow outlet, the level of the pulp, and the thickness of the layer of bubbles in the compartment C.

As regards the main compartment of the air cell A above the air box, the proper relation between the pulp level and the overflow lips 45 is obtained by adjusting the pulp level through the instrumentality of the ad- 120

justable overflow pipe 21. When this adjustment is made in such manner as to secure proper results in the main compartment of the cell A over the air box, it is necessary that the overflow means used in the compartment C be adjusted to correspond with the conditions found necessary to secure the best results in the main compartment of the air cell.

For this purpose I have provided in the compartment C an overflow tray 46 which is simply a vessel open at the top, having its sides 47 parallel, and its ends 48 converging downwardly to an outlet opening 49. The outlet opening 49 is connected by a flexible pipe or hose 50 with one of the main launders 44, if it be desired to mingle the concentrates obtained in the compartment C with the concentrates obtained from the main compartment of the cell A. If it is not desired to mingle the concentrates obtained from these two sources, the overflow tray 46 and its outlet opening 49 lead to such other point as desired. In some cases it may be desirable to return the concentrates obtained in the compartment C to the head of the machine to be re-treated with the incoming original feed. The overflow tray 46 is provided with suitable supporting means, such as a bail 51, having a slotted extension at its upper end coating with a slotted hanger 52, supported from any convenient point such as the air main 35. By means of a binding screw 53 and nut 54 the tray 46 may be supported at any desired height.

In operation the pulp, previously mixed with the necessary reagents, is admitted to the main compartment of the flotation cell A, through the port 3. During the passage of the pulp through the main compartment of the flotation cell the upwardly-coursing air bubbles from the air box B collect the metalliferous particles and carry them to the upper surface of the pulp where a mass of bubbles of varying thickness, according to conditions, is built up. The level 55 of the pulp is adjusted by turning the upper outlet pipe 21 to the proper point, this point being determined by the level necessary to obtain the best results in grade of concentrate and recovery in the mineral carried by the bubbles overflowing from the main compartment of the flotation cell. The pulp passes from the main compartment of the cell A through the opening 18 into the compartment C, part of the pulp flowing to waste through the lower tailings outlet 20, and part through the upper overflow pipe 21. While in the compartment C the partially depleted pulp is not supplied with air by reason of the fact that the flotation box B does not extend beyond the partition 8, but more or less air is contained in the pulp after it passes into the compartment C, and such air rises to the top and causes the for-

mation of a mass of mineral-carrying bubbles on the surface of the pulp in the compartment C. By reason of the fact that no air is supplied to the pulp in the compartment C, the mass of bubbles upon the surface of the pulp in that compartment will not ordinarily be as abundant and will not build up to so great a thickness as is the case upon the surface of the pulp in the main compartment of the vessel A. It would, therefore, be impracticable to collect the bubbles from the compartment C by overflowing them over a fixed lip, or a lip placed at the same elevation as the lips 45 over which the bubbles are carried from the main compartment. The overflow tray 46, however, may be adjusted to such height that the bubbles overlying the pulp in the compartment C will flow over the upper edges of the tray, as indicated by the arrows 60 in Fig. 1. These bubbles, consisting of water films, with the adhering metalliferous mineral, flow downward in the tray 46 and through the pipe 50 may be conducted to the main launders 44, or to such other place as desired. The adjustment of the slope of the porous bottom formed by the air box is easily accomplished by the means hereinbefore described, and when such adjustment is made the outlet opening 18 is kept constant by the movement of the lower movable section 8' of the partition 8. The tailings discharged through the upper adjustable outlet opening 21 may be received in a box 61 and conducted downwardly therefrom through a pipe 62 to the launder 63 which receives the tailings discharged from the lower end of the cell.

The structure illustrated in Fig. 6 of the drawings differs in no wise from that hereinbefore described, except in the fact that instead of employing a single adjustable air box B forming substantially the entire bottom of the main compartment of the cell A, I have constructed the bottom in the form of a plurality of air boxes D, D¹, D², D³, D⁴, D⁵, and D⁶. Each of these separate air boxes is similar in its general structural arrangement to the single air box B described in connection with the form of my invention illustrated in Figs. 1 to 5, differing therefrom only in size. When the porous bottom is constructed of a plurality of units, as illustrated in Fig. 6, the frame 4' is preferably provided with a plurality of cleats or shoulders 70, one for each section of the air box, thereby rendering each section of the air box independent of the other sections, and each section removable without disturbing any of the other sections. This arrangement facilitates repair and cleaning of the apparatus, and in some instances may be found preferable to the structure illustrated in Figs. 1 to 5, in which form while the porous bottom may be removed and re-

paired or cleaned expeditiously, it is necessary that the whole bottom be removed for that purpose.

While in the foregoing I have described my invention as embodied in a specific mechanical structure, the principle of my invention may, of course, be applied in mechanical forms of widely divergent character.

10 What I claim is:—

1. In an apparatus of the class described for treating ore pulp, a vessel, means for admitting air in a finely divided condition into the pulp in said vessel, means for admitting

15 pulp to said vessel at one end, a vertically adjustable pulp overflow discharge outlet in the opposite end of said vessel, and a valved pulp discharge outlet in the last mentioned end of said vessel adjacent the bottom 20 thereof.

2. In an apparatus of the class described for treating ore pulp, a vessel adapted to contain the pulp, an air box support in said vessel, means for setting said support in

25 positions of varying inclination, an air box having a porous top removably resting upon said support, and flexible air supply means connected to said air box.

3. In an apparatus of the class described for treating ore pulp, a vessel to contain the pulp, an air box support in said vessel pivotally mounted near one end of said vessel, means for raising and lowering the opposite end of said support to vary its inclination, 35 an air box having a porous top removably positioned on said support, and flexible air supply means connected to said box.

4. In an apparatus of the class described for treating ore pulp, a vessel to contain the

40 pulp, said vessel containing a main compartment and a supplemental compartment, the main compartment being separated from said supplemental compartment by a partition extending from the upper part of

45 said vessel to a point adjacent the bottom thereof, whereby said main and supplemental compartments have communication through a pulp discharge port beneath the lower edge of said partition, an air box having a porous upper side pivotally mounted

50 in said main compartment at the side thereof opposite said discharge port, an overflow bubble-collecting tray positioned in the upper part of said supplemental compartment,

55 and an upper overflow outlet communicating with the pulp mass at a point near the level of the lower edge of said partition.

5. In an apparatus of the class described for treating ore pulp, a vessel to contain the

60 pulp, said vessel comprising a main compartment and a supplemental compartment, a partition separating said compartments and extending from a point above the bottom of

65 said vessel to the upper part thereof, whereby said compartments are connected by a

discharge port beneath the lower edge of said partition, an air box having a porous top, said air box being pivotally mounted in said main compartment at the side thereof opposite said discharge port and inclining 70 downwardly toward said discharge port, and means for raising and lowering the end of said air box adjacent said discharge port and for raising or lowering the lower edge of said partition in accordance with the 75 movement of the lower end of said air box.

6. In an apparatus of the class described for treating ore pulp, a vessel to contain the pulp, a plurality of separately formed air boxes independently supported in said vessel 80 at a point beneath the level of the pulp contained therein, a source of air under pressure, and independent connections between said air source and each of said air boxes, and an inclined support for said boxes. 85

7. In an apparatus of the class described for treating ore pulp, a vessel for containing the pulp, said vessel being provided with inlet and discharge openings and lips over which the mineral-bearing bubbles flow, launders 90 for collecting the bubbles discharged over said lips, means for admitting air or other gas in a finely divided state beneath the surface of the pulp, said means extending across said vessel but terminating at a distance 95 from said discharge opening, and means for deflecting ascending bubbles in that part of the liquid not directly above the air admission means away from the discharge end of the vessel into the column of bubbles ascending directly above said air admission means, said deflecting means being at approximately the same height as the lips upon said vessel over which the said mineral-bearing bubbles flow. 100

8. In an apparatus of the class described for treating ore pulp, a vessel for containing the pulp, said vessel being provided with inlet and discharge openings and lips over which the mineral-bearing bubbles flow, 110 launders for collecting the bubbles discharged over said lips, a supplemental discharge duct adjustable in height to regulate the pulp level in said vessel, means for admitting air or other gas in a finely divided state beneath 115 the surface of the pulp, said means extending across said vessel but terminating at a distance from said discharge opening, and means for deflecting the ascending bubbles in that part of the liquid not directly above the air admission means away from the discharge end of the vessel into the column of bubbles ascending directly upward from said air admission means, said deflecting means being at approximately the same height as 120 the lips over which the said mineral-bearing bubbles flow.

9. In an apparatus of the class described for treating ore pulp, a vessel for containing the pulp, said vessel being provided with in- 125

let and discharge openings, an air box for admitting air or other gas in a finely divided state beneath the surface of the pulp, said box being inclined downward toward the discharge opening and spaced from it, a partition located in said vessel in line with the lower end of said box, said partition having a discharge opening beneath it adjacent to the lower end of said box, an adjustable member carried by said partition and operative to vary the size of said latter discharge

opening, and means for operating said adjustable member to vary said opening and simultaneously to adjust the position of said air box.

In testimony whereof, I have subscribed my name.

JAMES M. HYDE.
